UNITED STATES PATENT OFFICE.

PETER S. SORENSEN, OF NORTH MILWAUKEE, WISCONSIN.

REPRODUCER FOR PHONOGRAHS.

1,241,673.

Specification of Letters Patent.

Patented Oct. 2, 1917.

Application filed July 1, 1916. Serial No. 107,011.

To all whom it may concern:

Be it known that I, PETER S. SORENSEN, a citizen of the United States, and a resident of the village of North Milwaukee, in the 5 county of Milwaukee and State of Wisconsin, have invented certain new and useful Improvements in Reproducers for Phonographs; and I do hereby declare that the following is a full, clear, and exact description of the same, reference being had to the accompanying drawings, and to the numerals of reference marked thereon, which form a part of this specification.

Among the different kinds of phonographs and talking machines now on the market, are two generally well known types, one designed to use a needle tracing point or stylus to track over a flat disk record and the other adapted to use a jewel for the 10 purpose, and this difference in construction is due to the different character of records used on the two types of machines. The records for use on a machine using a needle point or stylus are provided with a sound 15 wave impression of one character while the records for use on the other type of machine are provided with sound wave impressions of another character. The one acts to set up the sound vibrations through the reproducer by causing a transverse movement of the reproducing point and the other by a substantially vertical or longitudinal movement thereof. In each instance the oscillation of the tracing point is transmitted to 20 a diaphragm whereby the sound is reproduced in accordance with the sound wave impression upon the record.

It is an object therefore of this invention to construct a reproducer which is capable 25 of universal use on either of the types of records mentioned by simple shifting movement of the tracing point, the tracing point in one position being capable of movement to reproduce sounds from one kind of record 30 and in another extreme position of adjustment capable of movement to reproduce sounds from another type of record.

It is also an object of this invention to 35 construct a reproducer for use on talking machines wherein the tracing stylus is pivoted in offset relation with respect to the diaphragm so as to be capable of vibrating or oscillating either transversely or longitudinally dependent upon its angle of adjustment with respect to the diaphragm to 40 permit the same to be used with different

types of records to reproduce sounds therefrom according to the particular sound wave impression on the record.

It is also an object of this invention to 45 construct a reproducer for talking machines capable of universal use upon different types of records, the tracing stylus being susceptible to longitudinal or transverse vibrations according to its position of adjustment.

It is furthermore an important object of 50 this invention to construct a reproducer for use on talking machines which is adjustable into different positions whereby vibrations of different character may be imparted thereto from the sound wave lines of 55 different character on different records used upon the machine.

It is finally an object of this invention to 60 construct an improved type of adjustable 65 reproducer simple in construction and operation and capable of being used on a record having either transverse sound wave 70 lines disposed in the plane of the record or those of constant radius but varying in 75 depth of impression on the record.

The invention (in a preferred form) is 80 illustrated in the drawings and hereinafter more fully described.

In the drawings:

Figure 1 is a fragmentary side elevation of a disk record playing machine illustrating the use of a reproducer embodying the principles of my invention thereon.

Fig. 2 is an enlarged side elevation of the 85 sound box mounted on the sounding arm.

Fig. 3 is a top plan view of the sounding arm showing the adjustable connection for supporting the sound box adjustably thereon.

Fig. 4 is a detail section taken on line 90 4—4 of Fig. 3.

Fig. 5 is a detail section taken on line 95 5—5 of Fig. 2.

Fig. 6 is a detail section taken on line 100 6—6 of Fig. 5.

As shown in the drawings:

The reference numeral 1, indicates as a whole a talking or sound reproducing machine having a rotatable table to receive a disk record 2, placed thereon for rotation 105 thereby. A pivoted sounding arm 3, is mounted at one side of the machine 1, and has an extension 4, connected thereto by a universal joint 5. Inserted into the end of the extension arm 4, is a tubular elbow 110 connection comprising a long tubular portion 6, engaged within the end of the ex-

tension 4, and communicating at right angles through a barrel or cylinder 7, rigidly associated therewith. Said barrel or cylindrical portion 7, is provided with an 5 end cap or cover 8, rigidly secured thereon in any suitable manner. Slidably inserted within the barrel 7, is a cylindrical member 9, having a peripheral shoulder or collar 10, which abuts against the open end of 10 the barrel 7. Rigidly secured in the cap 8, of the barrel 7, is a guide screw 11, having a coiled compression spring 12, wound thereabout and bearing upon the integral end wall of the inner cylinder 9. The marginal edge of the open end of the barrel 7, is provided with two recesses or notches 15 therein having the indicative numerals "1" and "2" marked adjacent thereto, and a pin 13, projects from the exterior of the cylindrical member 9, and is adapted to seat in one or the other of said recesses to hold said inner cylinder 9, in one or the other of the two possible positions by rotation within the barrel 9. A disk element 14, is provided 20 having a tubular hub extension 15, adapted to fit over the open end of the cylindrical member 9, secured releasably thereto by a pin or screw 16. A sounding diaphragm 17, is mounted in said disk 14, the assembly 25 affording a sound box, and is adapted to be set in vibration by a bell crank lever, one arm of which is denoted by the reference numeral 18, and bears centrally upon said diaphragm, and the other arm of which 30 is denoted by the reference numeral 19, and projects beneath and to one side of said disk element 14. Said disk element 14, is provided with a pair of lug extensions 20, between and in which is journaled a pivot 35 shaft 21, on which said bell crank 18-19 is mounted.

A set screw 22, is provided in said bell crank 18-19, adapted to be tightened upon the pivot shaft 20, to hold said bell crank 45 securely thereon. The arm 19, of said bell crank is provided with an aperture through the outer end thereof adapted to receive a needle or other tracing point or stylus 23, mounted securely therein, to track over the 50 record.

As shown in Fig. 2, a set screw 24, is provided threaded into the arm 19, at the opposite edge to tighten against the stylus or needle to hold the same securely therein.

55 The operation is as follows:

The two possible adjustments of the tracing stylus with reference to the arm 4, are shown in Fig. 2, one position being shown in dotted lines and the other in full lines.

60 Such adjustments are made by rotating the diaphragm head or disk member 14, such rotation being permitted by pulling outwardly to one side of the arm 4, to withdraw the inner cylinder 9, against the compression of its spring 12, and then rotating 65

said disk member together with said inner cylinder 9, until the pin 13, of said inner cylinder latches into one or the other of the notches "1" or "2", as the case may be.

With the stylus in one position of adjustment with reference to the tubular sounding arm 4, the tracing point is adapted to track upon one type of a playing record to reproduce sounds therefrom according to the sound wave impression thereon, and when 70 in the other position of adjustment, is adapted to track in another type of wave line impression of another record to reproduce sound therefrom. With the stylus adjusted to the full line position shown in 75 Fig. 2, the same is susceptible of transverse vibrations as it tracks upon the face of the disk record, and when adjusted into the dotted line position shown, is susceptible to 80 vertical vibrations caused by tracking in a wave line impression of another character 85 on another type of disk. The stylus by adjustment, is susceptible to both character of wave line impressions on different disk records due to the offset pivotal mounting of 90 the needle carrying arm whereby the needle carrying arm may pivot upon its pivot shaft to transmit different kinds of vibrations according to its adjustment.

I am aware that various details of construction may be varied through a wide range without departing from the principles of this invention and I therefore do not purpose limiting the patent granted otherwise than necessitated by the prior art.

100 I claim as my invention:

1. A reproducer for phonograph machines capable of use on different types of disk records comprising a diaphragm carrying head, a vibratory arm pivoted thereon, a tracing stylus mounted in said arm, resiliently connected means permitting adjustment of said diaphragm head to change the angle of contact of said stylus with the playing record, and a pin and notch mechanism 105 for retaining said diaphragm head in fixed 110 adjusted positions.

2. In a reproducer of the class described, a rotatable adjustable diaphragm head, means positively latching the same in different positions of adjustment, a vibratory arm pivoted on said head, a diaphragm mounted on said head contacted by said arm, and a tracing stylus mounted in said arm adapted to be shifted on said head to different angular positions with reference to 115 records played.

3. In a reproducer of the class described, a rotatable adjustable diaphragm head, a diaphragm mounted therein, a bell crank vibratory arm pivoted on said head with one arm contacting said diaphragm, a stylus mounted in the other arm of said bell crank, and resilient interlatching means to latch 120 said diaphragm head in different positions 125 130

of adjustment to vary the angle of contact of said stylus with a playing record.

4. In a device of the class described the combination with a tubular arm, of a cylindrical extension thereon, a sound box comprising a diaphragm head, a cylindrical member associated therewith and interfitting with said cylindrical member on the arm, a spring coiled within said interfitting cylindrical members to hold the same resiliently associated with one another and permitting rotation or adjustment thereof, and a pin and latch mechanism between said cylindrical members to lock the sound box in different adjusted positions with respect to said cylindrical member on said arm.
5. In a device of the class described, a tubular arm, an integral cylindrical extension thereon, a sound box comprising a diaphragm head, a diaphragm mounted there-

in, a reproducing needle connected with the diaphragm head and with the diaphragm to vibrate the same, a cylindrical member associated with the diaphragm head and interfitting with said cylindrical extension, resilient means affording connection between said cylindrical member and said cylindrical extension permitting rotational adjustments of the diaphragm head, and a pin and slot latching means between said cylindrical member and said cylindrical extension to latch the diaphragm head into different adjusted positions.

In testimony whereof I have hereunto subscribed my name in the presence of two 35 subscribing witnesses.

PETER S. SORENSEN.
